GAS-ENGINE.

No. 901,745.

Specification of Letters Patent. Patented Oct. 20, 1908.

Application filed September 2, 1905. Serial No. 276,785.

To all whom it may concern:

Be it known that I, ANTON SCHIEFERSTEIN, a citizen of the United States, and a resident of Bayonne, in the county of Hudson and State of New Jersey, have invented certain new and useful Improvements in Gas-Engines, of which the following is a specification.

This invention relates to hydro-carbon engines, gas engines and the like with means for introducing into the cylinders and exploding chambers thereof, charges of air to cool and disinvest the same of spent gases and the like. Its organization is characterized by a compressor or air pump, operating in conjunction with and forming part of an engine, the said compressor or air pump having in its moving mechanism a pair of elliptic gears, to enable the charge from the air pump to enter the working cylinder of the engine, during its discharge of spent gases. The elliptic gears drive the compressor piston on its up-strokes at about the same speed as the speed of the piston in the working cylinder of the engine.

In the drawings the invention is shown with a four cycle engine.

Figure 1 shows an elevation and partial axial section of the invention, Fig. 2 is a section of Fig. 1 on the line x , x , Fig. 3 represents an end view of Fig. 1.

An air pump or compressor cylinder A, has mounted thereon the head B, containing the usual inlet valve B', with its inlet pipe C, and outlet valve B'' with its outlet pipe D. The cylinder is supported on the frame E, and contains the piston A'. The latter is joined with the connecting rod F, which is actuated by means of the wrist pin F' extending from the elliptic gear G at its revolving focus. The said gear is supported on the shaft G' whose axis is in line with the stationary focus of said gear, the shaft G' being supported by the hub G''. An elliptic gear H meshes with the gear G, and is supported on the shaft H' passing through its stationary focus, and which in the present case is in the same horizontal plane with the shaft G'. The shaft H' is supported in the bearings H''.

Adjacent to the frame E, and connected thereto by the connecting portions H'', is the frame J of the engine, that is to co-set with the air pump, and in this case is represented as a gas engine, having the cylinder K with the piston K', head L, and exhaust valve chamber M', with the exhaust valve

M. Within the frame J are the journal bearings J', J'' for the crank shaft N, that is joined with the connecting rod N', and which latter is connected with the piston K'. The said crank shaft has mounted thereon the pinion N'', which meshes with a gear I fastened to the shaft H', and is, in this case, about double the diameter of the said pinion. On the shaft N is also secured the bevel pinion O, that meshes with the bevel gear O', which latter is fastened to the vertical shaft P carrying the bevel gear Q. The latter bevel wheel meshes with the gear Q' on the shaft R, that carries a cam R', which actuates the valve spindle T of the exhaust valve M.

A gas inlet valve for the cylinder K is shown at 10 with the gas inlet pipe 11. A spark plug 12 is connected to the head L and is in circuit with the battery 14 by means of the wire 15. A wire 17 leads to an insulated pin 18. A spring 19 with the terminal 20 is actuated by a cam 21 to open and close the circuit for the spark plug 12.

For a two cycle gas engine, the pinion N'' and gear wheel I would be made of approximately equal diameters.

The outlet pipe D of the compressor or air pump connects with the cylinder K, and has a check valve V, adjacent to the cylinder K.

When operating the invention the gas engine drives the compressor through the train of gearing as shown. The pinion N'' makes two revolutions for each revolution of the wheel I, and the elliptic gears are proportioned so that the up stroke of the air pump piston, is made in about the same interval of time, as every second up stroke of the gas engine, so that the air from the compressor enters the cylinder of the gas engine when the latter is open to the exhaust.

The exhaust valve of the gas engine opens at about the commencement of every second up stroke of its piston, and the air or other gas from the air pump will be forced therein at the proper time, to cool and clean the cylinder of the gas engine of its spent gases.

Having described my invention, I claim:

1. The combination with a gas engine of an air pump, a conduit connecting the outlet of the air pump and the cylinder of the engine, a shaft for the engine and a shaft for the air pump, a pair of elliptic gears connected up between said shafts so that the discharges from the air pump will be forced

into the cylinder of the engine during the intervals that the spent gases are exhausted from the latter.

2. The combination with a gas engine of
5 an air pump, a pipe connecting the discharge opening of the air pump and the cylinder of the gas engine, a crank shaft for the engine, a pinion on said shaft, a crank shaft for the air pump, a third shaft between said
10 shafts, a gear wheel on the third shaft meshing with said pinion, an elliptic gear on the third shaft, an elliptic gear on the shaft of the air pump, the elliptic gears meshing

with each other, and proportioned so that each up stroke of the air pump will be made 15 in the same interval of time as every second up stroke of the engine, to force air from the air pump into the cylinder of the engine when the latter is exhausting its spent gases.

Signed at Bayonne, in the county of Hudson and State of New Jersey this twenty-sixth day of August, A. D. 1905.

ANTON SCHIEFERSTEIN.
